UNITED STATES PATENT OFFICE.

VICTOR E. RUMBARGER, OF DAYTON, OHIO.

ELECTRICAL DISPLAY.

1,113,250.

Specification of Letters Patent.

Patented Oct. 13, 1914.

Application filed January 14, 1909. Serial No. 472,177.

To all whom it may concern:

Be it known that I, VICTOR E. RUMBARGER, a citizen of the United States, residing at Dayton, in the county of Montgomery and State of Ohio, have invented certain new and useful Improvements in Electrical Displays, of which the following is a specification, reference being had therein to the accompanying drawings.

10 This invention relates to electrical displays. In many displays of this character it is desirable that the light of the lamp or lamps comprising the same should be so confined that the figure formed thereby will 15 be sharply defined against the background.

To this end the object of the present invention is to provide a shield or housing forming a compartment adapted to receive a lamp and to inclose the same on all but one 20 of its sides; to provide such a shield which will be readily removable and interchangeable; and which will be supported by the lamp itself; to provide means for retaining the shield in position on the lamp and for 25 preventing electrical contact between the shield and the lamp base; further, to provide such a shield which can be formed in the shape of a fanciful figure and which can be utilized either individually or in 30 series to form the desired display and which will be of such a construction that, when a plurality of lamps provided with shields are arranged close together to outline a figure, the several lamps will form a practically 35 continuous line of light which will be sharply defined against the background; and further, to provide such a shield which will be inexpensive and easily attached to any ordinary incandescent electric lamp.

With these objects in view my invention consists in certain novel features and in certain combinations and arrangements of parts to be hereinafter described, and then more particularly pointed out in the claims.

5 In the accompanying drawings, Figure 1 is a front elevation of an electrical display formed of a series of lamps equipped with my invention; Fig. 2 is a side elevation of a lamp and shield; Fig. 3 is a vertical, sectional view taken centrally through Fig. 2; Fig. 4 is an end view of a lamp provided with a shield formed in the shape of a star; and Fig. 5 is a sectional view taken on the line $\alpha\alpha$ of Fig. 4 and looking in the direction of the arrows.

In these drawings I have illustrated the preferred form of my invention, and, in Fig. 1, I have shown an electrical display comprising a heart-shaped figure formed of a series of lamps equipped with independent shields in accordance with my invention. It will be understood, however, that the figure here shown is chosen for the purpose of illustration only and that the invention is adapted for use in a great variety of displays and signs and that it is particularly adapted for use in forming letters.

The invention may be adapted for use with a lamp of any suitable character, and, in the present invention, I have shown the same in connection with the ordinary incandescent electric lamp comprising a bulb 1 having a base 2 adapted to enter and be supported by a lamp socket 3, which, in turn, may be secured to any suitable support.

In carrying out my invention each lamp is provided with a shield or housing 4 extending about the same and forming a compartment within which the bulb of the lamp is confined. This compartment is open on one side only, preferably at the side adjacent to the outer end of the lamp, and, consequently, the lamp is visible at this end only, thus causing the end of the shield within which the lamp is mounted to be sharply outlined by the light of the lamp within the same. This shield is preferably removably mounted so as to be readily interchangeable and is, in the present instance, supported by the lamp itself, being provided with suitable means to prevent electrical contact between the shield and the lamp base. The shield may be formed of any suitable material, but is preferably formed of metal and is of such a character that it may be provided on its inner side with a reflecting surface to intensify the light of the lamp. In the form of device here shown, the shield is formed of metal and is substantially circular in cross section having its sides converging inwardly, i. e., toward the lamp socket 3. The walls of the shield converge to such an extent as to provide the shield with an opening at the inner end thereof of a size such as to permit the lamp base to pass freely through the same, but such as to cause the inner edges of the shield to engage the bulb of the lamp at a point slightly removed from the base thereof. In order to support the

shield in this position upon the lamp and also to prevent electrical contact between the shield and the base 2 I prefer to provide a band of non-conducting material, such as a ring of elastic rubber 5, which fits snugly about the lamp at the inner end of the shield and not only retains the same in position on the lamp, but also interposes a layer of non-conducting material between the shield and the lamp base, thereby preventing a short circuit when the shields for the adjacent lamps of a display are in engagement with each other. Further, the ring of rubber prevents moisture from entering the inner end of the shield or the socket. By so supporting the shield upon the lamp the lamp and shield may be handled as a single device, thereby enabling the lamp and shield to be simultaneously secured to the support or removed therefrom. At the same time, it requires but a very small amount of time and slight effort to separate the shield from the lamp. The outer end of the shield preferably terminates in substantially the same transverse plane with the end of the lamp bulb 1 and the outer portion thereof may be of any suitable configuration, and, in the form shown in Figs. 2 and 3, it is flared outwardly to form a round figure or a solid ball of light. The diameter of the shield is preferably slightly greater than the diameter of the lamp taken on the same transverse line or plane, and, consequently, the shield comes in contact with the bulb only at its inner edge, and, while the line of contact extends entirely about the bulb, it is very narrow, and, consequently, a minimum amount of heat is conducted from the bulb to the shield.

While I have shown and described the shield as having its sides converging inwardly so that they are substantially parallel with the side of the lamp, it will be understood that this specific construction is not an essential feature of the invention and that the desired results may be obtained with shields of other shapes, it being only necessary that the shield shall fit comparatively closely about the lamp and shall prevent the lateral diffusion of the light.

In Figs. 4 and 5 I have shown the shield with its outer end in the shape of a star, the star being preferably formed by pressing the material forming the shield outwardly at suitable points to form the points of the star. Thus, the light of the lamp within the shield will be confined within a star-shaped shield and only the sharply outlined star will be visible against the background. The points 6 of the star preferably begin to diverge from the line of the side wall of the shield at a point near the point of greatest diameter of the bulb 1 and gradually diverge therefrom, thus causing the walls

forming the points of the star to converge inwardly and merge with the walls of the shield.

It will be apparent that both the figure outlined by a series of lamps and those formed by the ends of the shields, as shown in these drawings, are used for purposes of illustration only and that the shield may be formed in the shape of any desired figure and that a plurality of lamps, with the shields forming either plain or fanciful figures, may be assembled to form any desired display. It will also be apparent that the shape of the shield itself and the manner of the support thereof may be varied without departing from the spirit of the invention, and I therefore wish it to be understood that I do not desire to be limited to the details of construction shown and described, for obvious modifications will occur to a person skilled in the art.

Having thus fully described my invention, what I claim as new and desire to secure by Letters Patent, is:—

1. The combination, with a lamp comprising a bulb and a base, of a shield completely encircling said bulb, and means for supporting said shield on said lamp with the inner surface of said shield out of engagement with the surface of said bulb, said shield having its inner end arranged near the inner end of said bulb and having its outer end terminating beyond the light-giving element of said lamp, thereby preventing the lateral diffusion of light by said lamp and causing the open end of the shield to be sharply defined by the light within the same.

2. The combination, with a lamp comprising a base and a bulb, of a shield extending entirely around said bulb and having a substantially cylindrical outer portion of a diameter slightly greater than the largest diameter of said bulb, and means for supporting said shield in position about said bulb with its inner surface close to but out of contact with said bulb.

3. The combination, with a lamp comprising a base and a bulb, of a shield encircling said bulb and extending from a line near the inner end of said lamp to a line near the outer end of said bulb and even with or beyond the outer end of the light-giving element of said lamp and having its outer end open, thereby preventing the lateral diffusion of light and causing the outer end of the shield to be sharply defined by the light within the same, and means for supporting said shield with its inner surface close to but out of contact with said bulb.

4. The combination, with a lamp comprising a bulb and a lamp base, of a shield extending about said bulb and having a circumferential wall spaced away from said bulb, converging toward said base and engaging said bulb at a point beyond said base,

- and means for maintaining the end of said shield in contact with said bulb.
5. The combination, with a lamp comprising a bulb and a lamp base, of a shield extending about said bulb, having its outer end adjacent to the outer end of said bulb and beyond the light giving element thereof and having its circumferential walls spaced away from said bulb, converging toward said base and engaging said bulb at a point adjacent to said base, and means for retaining said shield on said lamp and for preventing electrical contact between the shield and the base.
- 10 6. The combination, with a lamp comprising a bulb and a lamp base, of a shield extending about said bulb, having its outer end adjacent to the outer end of said bulb and beyond the light giving element thereof and having its circumferential walls spaced

away from said bulb, converging toward said base and engaging said bulb at a point adjacent to said base, and a band of insulating material extending about said lamp between said shield and said base.

25

7. The combination, with a lamp comprising a bulb and a lamp base, of a metallic structure extending closely about said bulb and spaced away therefrom except at its inner end, and a ring of insulating material mounted on said lamp to hold said inner end of said metallic structure in engagement with said bulb and out of engagement with said base.

30

In testimony whereof, I affix my signature in presence of two witnesses.

VICTOR E. RUMBARGER.
